UNITED STATES PATENT OFFICE

165,687

AIRPLANE

Clarence L. Johnson, Encino, Calif., assignor to
Lockheed Aircraft Corporation, Burbank, Calif.

Application November 30, 1950, Serial No. 13,193

Term of patent 14 years

(Cl. D71—1)

To all whom it may concern:

Be it known that I, Clarence L. Johnson, a citizen of the United States, residing at Encino, county of Los Angeles, State of California, have invented a new, original, and ornamental Design for an Airplane, of which the following is a specification, reference being had to the accompanying drawing, forming a part hereof.

Figure 1 is a perspective view of the airplane of my design, shown without wing tanks, while in flight, taken from a point in front, to the side, and slightly above;

Figure 2 is a front view of Figure 1 with extended landing gear, and wing tip tanks shown in dotted lines;

Figure 3 is a side view of Figure 2 without the wing tanks;

Figure 4 is a top view of Figure 2; and

Figure 5 is a rear view of Figure 2.

The characteristic features of my design reside in those portions shown in full lines in the drawings.

I claim:

The ornamental design for an airplane, as shown and described.

CLARENCE L. JOHNSON.
